UNITED STATES PATENT OFFICE.

CHARLES F. STOKES, OF WASHINGTON, DISTRICT OF COLUMBIA, ASSIGNOR
TO CHARLOTTE B. STOKES, OF WASHINGTON, DISTRICT OF COLUMBIA.

SPLINT-STRETCHER.

No. 820,026.

Specification of Letters Patent.

Patented May 8, 1906.

Application filed July 21, 1905. Serial No. 270,708.

To all whom it may concern:

Be it known that I, CHARLES F. STOKES, a citizen of the United States, residing at Washington, District of Columbia, have invented certain new and useful Improvements in Splint-Stretchers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in splint-stretchers for transporting wounded or disabled persons with comfort and a sense of security to the patient, and comprises means for splinting the entire body, as well as the immobilizing of the injured parts, and affording an apparatus for the transportation of a person with a minimum amount of direct handling of the head, trunk, and extremities.

Heretofore it has been the practice to use transporting-boards having buttock-pieces so placed that they throw the upper fragments forward in fractures of the femur, and the foot-pieces tend to put the broken bones out of line or crowd their ends together in fractures of the leg, and devices of this kind made of wood are a source of great danger through splintering when used on fighting-ships. While certain types of litters have restraining and securing attachments, none, so far as I am aware, provide means for splinting the entire body, which is essential in order to handle satisfactorily and efficiently severe crushing injuries of the leg or very oblique fractures of the tibia or the same types of injury of the thigh.

The invention consists, further and specifically, in the provision of a basket-shaped receptacle made, preferably, of a hand-woven meshwork of wire and so arranged that portions of the frame may be utilized as runners, if desired, to raise and lower the apparatus down a ladder or stairway and so constructed that the same may be conveniently lowered through a hatchway or from a scaffold.

The invention comprises, further, an improved splint-stretcher adapted to receive the body of a patient and provided with suitable handles for convenience in carrying the apparatus, to which the patient may be held

by suitable bandages or strips, and provided with gutters to receive the legs of a person, and an adjustable foot-piece which may be held at different positions within the gutters, whereby when the foot of a patient is secured to the foot-piece inward and outward rotation may be prevented when handling the patient with fractures of the femur, the mesh of the apparatus being sufficiently pliable to be shaped to the part it contains and of sufficient rigidity for effective splinting.

The invention consists, further, in various other details of construction and in combinations and arrangements of parts, which will be hereinafter fully described and then specifically defined in the appended claims.

I illustrate my invention in the accompanying drawings, which, with the letters of reference marked thereon, form a part of this application, and in which—

Figure 1 is a perspective view of the framework of my improved splint-stretcher, showing the meshwork removed. Fig. 2 is a plan view of the apparatus with the meshwork applied thereto. Fig. 3 is a cross-sectional view on line 3 3 of Fig. 2. Fig. 4 is a cross-sectional view on line 4 4 of Fig. 2. Fig. 5 is a detail perspective view of a portion of the meshwork, showing the manner of construction of the same; and Fig. 6 is an enlarged detail view of one of the adjustable foot-pieces.

Reference now being had to the details of the drawings by letter, A designates a bar of metal, which may be of any size or shape, forming the marginal edge of the stretcher, and B B designate two longitudinal bars or strips of metal, which are curved, as at B', near each end, forming means whereby the weight of the apparatus may be rested, and serving as runners to allow the apparatus to be conveniently lowered down inclines or over other objects without interference with the same. The ends of said strips B are fastened to the marginal bar A in any suitable manner, as by rivets C, and adjacent to each end of the stretcher and mounted upon the marginal bar A are the handle-grips D, whereby two or more persons may conveniently transport or carry the apparatus from place to place. Arranged at intervals are the cross pieces or braces E, which have curved ends riveted or otherwise secured to the marginal bar A, as at E'. Said cross-pieces E are also riveted or securely fastened

the strips forming the runners B at the points of intersection of the same.

Substantially one-half the length of the stretcher is formed into two gutters, (designated in the drawings by letters F,) said gutters being formed by a bar H, which is supported by means of the upturned ribs K, bent as shown in the drawings and made of sufficiently rigid metal to hold said bar H in a plane parallel with the marginal bar A of the frame, each curved portion of the ribs K being fastened, as at K', by means of a rivet or other suitable fastening to the runner-pieces B. The inner end of the bar H is bent at a right angle at H' and is next bent to form a circle H¹, which rests upon a brace B¹ connecting runner-pieces B, said circle forming a means for holding the portion of the bar separating the gutters rigid and also serving as a sanitary opening.

At suitable locations along the opposite sides of the marginal bar A are formed the loops Q, the ends of which are twisted about said bar and serve as means for allowing persons to grip the bar for convenience in carrying the stretcher, one of said loops at the forward end of the apparatus being divided so that a tackle may be conveniently connected thereto when a patient within the stretcher is upturned for the purpose of lowering the same from any elevation, as from a scaffolding or from the deck of a ship, through a hatchway, &c.

A suitable meshwork, preferably of metal, (designated in the drawings by letter M) forms a lining to the framework described, the marginal edges of said meshwork being securely fastened to the frame and about the loops which form handle-openings, as shown clearly in the drawings. Two wide bands of canvas, (designated in the drawings by letters S and S') one positioned at the height of the axillæ and the other at the point of the hip are provided, which are anchored to the meshwork by means of retaining-chains R, having snap-hooks for engagement with the meshwork and which are provided for securing the thorax and pelvis, respectively.

Mounted within each gutter are the wire-gauze splints J J, which are anchored at intervals to the meshwork, forming the bottom of the stretcher, and also mounted in each gutter is an adjustable foot-piece, (represented by letters I,) an enlarged detail view of one of the same being shown in Fig. 6, said gutters, with the accessories named, forming two complete fracture-boxes, whereby in the field or in the street at a first dressing the indications so carefully looked after in hospitals afterward may be efficiently met. Each foot-piece, which is preferably of steel, is of a shape to conveniently fit the gutter and is provided with parallel slots i adjacent to the opposite edges thereof for the purpose of securing bandages, and at the outer marginal

edge of said foot-pieces are the snap-hooks I', forming convenient means for engaging the meshwork forming the bottom of each gutter. By this means it will be noted that the snap-hooks, which are rigid, may be adjusted and held at different locations in the leg-gutters to satisfy the different lengths of legs of patients. When not in use, said foot-pieces may be turned flush with the sides of the leg-gutters and snapped into the mesh in that position.

It will be observed that the mesh of the apparatus is sufficiently pliable to be shaped to any particular part it contains and is sufficiently rigid for effective splinting, and by the provision of the foot-piece when the foot of a patient is secured thereto inward and outward rotation may be effectually prevented in handling patients with fractures of the femur.

By the provision of a splint-stretcher embodying the features of my invention it will be noted that not only is the entire body protected on three sides, but the thorax and pelvis are secured, and the hip, knee, ankle, and foot of one or both sides may be immobilized in a few seconds, and when a patient has once been adjusted to my improved apparatus he will be impressed with his security and protection, which inspires him with confidence and adds to his comfort during removal. By means of a splint-stretcher embodying the features of my invention the apparatus, and not the patient, is gripped in manipulations incident to transportation.

By the peculiar shape of stretcher having runners upon the bottom thereof a patient fastened to the stretcher may be conveniently lowered down stairways, ladders, or other elevations up-ended, and when the stretcher is in a perpendicular position will keep his perineum away from the perineal fold by putting his weight upon the foot-piece upon the uninjured side. In the event of both legs being injured a bandage may be passed behind the neck over the shoulders and under the arms and secured to the meshwork will clear the perineum. By the peculiar shape of my improved splint-stretcher it will be noted that a plurality of the same may be conveniently nested together when desired to do so for storage or transportation, thus economizing in space, and when desired the stretchers may be suspended within cars or upon shipboard as hammocks are commonly hung.

While my improved splint-stretcher was originally devised to meet the requirements of naval service, it will be understood that the apparatus has a wider field, the invention being adapted equally well for civil-hospital-ambulance purposes, affording means where injured persons may be carried in police-patrol wagons to hospitals unattended by surgeons, thus minimizing mishaps due to un-

skilled handling in removing patients from 5 tenement-houses, through narrow passages, &c.

While I have shown a particular shape of 5 apparatus which I have found well adapted for the various purposes for which the invention is intended, it will be understood that the 10 same may be varied in different ways to meet different conditions, if desired, without in 15 any way departing from the spirit of the invention.

Having thus fully described my invention, 20 what I claim as new, and desire to secure by Letters Patent, is -

1. A splint-stretcher, comprising a suitable 25 frame, provided with a meshwork secured thereto and having leg-gutters, and means for fastening a patient to said stretcher, as set forth.

2. A splint-stretcher, comprising a suitable 30 frame, provided with a meshwork secured thereto and having leg-gutters, a foot-piece mounted in each of said gutters, and means for fastening a patient to said stretcher, as set 35 forth.

3. A splint-stretcher, comprising a suitable 40 frame, provided with a meshwork secured thereto and having leg-gutters, adjustable foot-pieces, one mounted within each gutter, and means for fastening a person to said 45 stretcher, as set forth.

4. A splint-stretcher, comprising a suitable 50 frame, provided with a meshwork secured thereto and having leg-gutters, foot-pieces, one mounted within each gutter, and provided with rigid snap-hooks, designed to engage 55 said meshwork and slotted to receive bandages, as set forth.

5. A splint-stretcher, comprising a frame 60 made up of longitudinal strips, which are curved to form runners, a marginal bar having handle-grips thereon, a rod extending centrally partially the length of the stretcher, and a meshwork over said rod, thereby forming 65 leg-gutters, as set forth.

6. A splint-stretcher, comprising a frame 70 made up of longitudinal strips with their ends curved, forming runners, a marginal bar to which the ends of said runners are fastened, handle-grips upon said marginal bar, cross- 75 pieces connecting the opposite portions of the latter and fastened to said runner-strips, leg-gutters formed in a portion of said stretcher, 80

a meshwork secured to said frame, and bandages secured to said stretcher, adapted to fasten 85 a person thereto, as set forth.

7. A splint-stretcher, comprising a frame 90 made up of metallic strips, their ends curved and forming runners, a marginal bar, cross-pieces fastened to said runner-strips and to 95 said marginal bar, leg-gutters extending partially the length of said stretcher, mesh splints anchored to said gutters, and means for fastening a person to said stretcher, as set forth.

8. A splint-stretcher, comprising a frame 100 made up of longitudinal strips with their ends curved, forming runners, a marginal bar to which the ends of said strips are fastened, a rod extending partially the length of the 105 stretcher, and dividing a portion of the stretcher into leg-gutters, and having cross-bars fastened at their middle portions to said rod and at their ends to the marginal bar of the stretcher, and a meshwork fastened to said frame and forming a bottom for the 110 stretcher, as set forth.

9. A splint-stretcher, comprising a frame 115 made up of longitudinal strips, the ends of which are curved to form runners, a marginal 120 bar connected to the ends of said runners, cross-pieces fastened to said runner-strips and marginal bar, a rod fastened at one end to said marginal bar and bent at a right angle, with its other end bent to form a ring, 125 curved cross-bars which are bent at their middle portions and fastened to said rod, with their ends secured to said marginal bar, a meshwork covering said rod and frame and secured to the marginal edge of said ring, 130 splints secured to said meshwork, and bands fastened to said splints, as set forth.

10. A splint-stretcher, comprising a frame, 135 a meshwork secured thereto, a portion of said frame being formed into leg-gutters, a marginal bar upon said frame, loops secured to 140 said marginal bar, and to which loops portions of the edge of said meshwork are fastened, and handle-grips mounted upon the marginal bar of said frame between the ends of said loops, as set forth.

In testimony whereof I hereunto affix my 145 signature in the presence of two witnesses.

CHARLES F. STOKES.
